UNITED STATES PATENT OFFICE

WILLIAM O. MCKAMEY, OF KNOXVILLE, TENNESSEE, ASSIGNOR TO SANFORD INVESTMENT COMPANY, OF WILMINGTON, DELAWARE, A CORPORATION OF DELAWARE

WHEEL AND AXLE

Application filed February 6, 1929. Serial No. 337,865.

This invention relates particularly to such wheels and axles as are adapted to form parts of mine cars or similar cars.

The object of the invention is to provide an efficient and durable wheel structure surrounding the end of the car axle and suitably secured to the axle for free or "loose" rotation on the axle.

In the accompanying drawings,

Fig. 1 is an upright section on the axial line of the wheel and axle;

Fig. 2 is a transverse section on the line 2—2, of Fig. 1, looking toward the left;

Fig. 2a is a section on the same line, looking toward the right;

Fig. 3 is a transverse section on the line 3—3, of Fig. 1, looking toward the left;

Fig. 4 is a horizontal section on the line, 4—4, of Fig. 1;

Fig. 4a is section similar to Fig. 4, with a few variations;

Fig. 5 is a horizontal section on the line, 5—5, of Fig. 1;

Fig. 6 is a transverse section on the line, 6—6, of Fig. 1, looking toward the left;

Fig. 7 is an elevation of the end of the wheel hub;

Fig. 8 is a section similar to Fig. 4, with a bolt substituted for the grease screw;

Fig. 9 is an elevation showing the outer face of the cap, detached from other part;

Fig. 10 is a plan of the same cap showing the locking plate in position on the outer end of the cap, and a part of the cap being broken away;

Fig. 11 is an elevation of the locking plate;

Figs. 12 and 13 are detail sectional views of other forms of the locking plate.

Referring to said drawings, A is one of the journals of a car axle to which my improvement is applied. B is a car wheel surrounding the journal. B1 is the hub of the wheel. B2 is the inner end wall of the hub. A steel or other hard metal lining, D, lies against the inner, horizontal face of the hub.

A group of horizontal antifriction rollers, C, fill the space between the journal, A, and the lining, D. All the rollers have between their ends a circumferential groove, C1. A

ring, C2, loosely surrounds the journal and extends into the grooves, C1.

From a little beyond the outer or right hand ends of the rollers, C, (as shown in Fig. 1) the hub, B1, has an outward extension, B 55 3, whose interior diameter is a little larger than the interior diameter of the main part of the hub. Thus there is formed an annular shoulder, B6, near the ends of the rollers and facing outward or toward the right. 60

Near the end of the journal, A, is a transverse aperture, A1, which receives a cross-pin or cotter pin, G, having a head, G1, larger than the aperture, A1. The lower end of the cotter pin is slotted and spread to form arms, G2, which prevent the cotter pin from moving upward in the journal. Between the cotter pin and the adjacent ends of the rollers, C, is a washer, F2, lying against the cotter pin. At the head, G1, of the cotter pin, said washer 70 is slotted to form tongues, F3, bent laterally to place one tongue against each side of said head, whereby the washer is held immovably on the journal. Between that washer and the ends of the rollers is a ring-form plate, F, which lies against the washer, F2, and against the hub shoulder, B6. On the periphery of the plate, F, are two diametrically opposite notches, F1, which receive inward extensions, B7, of the hub wall. Thus the plate, F, is 75 engaged to be rotated with the hub. Said notches, F1, are made deeper than the wall extensions, B7, whereby a passage is formed for the passing of lubricant, as will be described further on. 80

A cap, E, (shown in detail in Figs. 1, 9 and 10) fits slidably into the interior of the hub extension, B3, and has a flange, E3, which bears against a gasket, E4, composed of elastic material and lying against the rim of the flange, E3. Said gasket lies against the ring-form plate, F. When the cap, E, is pressed toward the right, as viewed in Fig. 1, the gasket, E4, is pressed against the plate, F, whereby said plate is pressed against the hub shoulder, B6. 85

A screw, E6, extends through the hub wall, B3, into a horizontal groove, E7, in the cap, E, to compel rotation of the cap with the hub. 100

Said groove allows limited horizontal movement of the cap.

The cap, E, has on its axial line a chamber, E1, adapted to receive a polygonal nut, 5 N, the sides of the chamber being formed to engage the nut, whereby the nut is held against rotation independently of said cap. From the chamber, E1, ducts, E2, lead to and through the inner face of the cap, E. 10 Those ducts serve to conduct lubricant to the interior of the cap, as will be described further on.

Along the outer face of the cap, E, the inner face of the hub wall, B3, is provided with 15 a channel, B5, which receives the end edges of the locking plate, H. (Figs. 1, 6, 7, 9, 10 and 11.) Said plate has two opposite parallel edges, H1. Between those edges are end edges, H2, concentric to the axial line of the 20 cap, E, and the hub; and the length of said plate is sufficient to bring the edges, H2, into the channel, B5, when said plate is in working position on the hub. The channel, B5, is so positioned as to cause the locking plate to 25 bear against the adjacent upright face of the cap, E, and at the same time bear against the outer or right hand channel wall. The cap, E, has in its outer face a recess, E5, as wide 30 as the width of the locking plate and as deep as the thickness of that plate.

The locking plate has a central aperture, H3, which is smaller than the chamber, E1. Hence the nut, N, is retained in the recess or 35 chamber, E1, when the locking plate is in position. Between the nut and the locking plate, a sealing gasket, H4, surrounds the aperture, H3, the gasket being pressed between the locking plate and the nut. The locking plate is to be made sufficiently flexible 40 to allow it to be sprung to force its end edges, H2, into the channel, B5. Since the adjacent end of the cap, E, is close to the channel, B5, the locking plate offers large resistance to the outward movement of the cap, 45 the outer face of the channel forming an abutment against which the cap presses the outer part of the locking plate. When the locking plate has been put into position, any suitable closing member may be extended 50 through the aperture, H3, of the locking plate and into the nut for closing the passage through the nut to the lubricant ducts, E2, and drawing the nut against the gasket, H4. The part of the closing member outside the 55 locking plate is to have a shoulder to engage the locking plate for limiting upward movement of the closing member. Such closing member is preferably a grease screw, I, of well-known form, said screw being adapted 60 to receive connection with the discharge member of a lubricant serving device, sometimes called a grease gun.

When the locking plate is to be removed for releasing the cap, E, as a preliminary to removing the wheel, the grease screw or other

closing member is removed and a bolt, J, substituted (Fig. 8), the bolt being rotated sufficiently to cause the threaded end of the bolt to press against the face of the cap, whereby the nut is forced outward against the locking plate sufficiently to spring said plate until the end edges of the locking plate are released from the channel, B5.

The middle, inner part of the inner face of the cap, E, is made convex so as to adapt it to bear against the central part of the end face of the journal; and said part of the cap is "chilled" to make it hard, whereby it is adapted to resist wear during rotation of the hub in contact with the journal.

It will now be noted that endwise thrust of the axle journal toward the right, as shown in Fig. 1, will be taken by said convex face of the cap, E, and that thrust of the axle journal toward the left will be taken by the ring-form plate, F, and the washer, F2, and the cotter pin, G. During rotation when the axle thrust is toward the left, the friction incident to such rotation is taken by the washer, F2, and the adjacent faces of the ring-form plate, F, and the cotter pin, G.

Lubricant is to be introduced through the grease screw, I, and the nut and the ducts, E2, in the cap, E. Thence the flow is around the end of the journal and the washer, F2, and through the notches, F1, of the ring-form plate, F, and thence into the spaces between the anti-friction rollers, C. In Fig. 4a and Fig. 8, the ducts, E2, are extended farther away from the axial line of the cap.

Diametrically opposite each other and in the plane of the cotter pin, G, are apertures, B4, of sufficient size to permit the passing of the cotter pin when the cap, E, is not in position in the hub.

For assembling, the hub lining, D, and the rollers, C, and the ring, C2, are placed into the hub and around the journal, A. Then the ring-form plate, F, and the washer, F2, and the gasket, E4, are placed into position around the journal and within the hub. Then the cotter pin is inserted through one of the apertures, B4, into the transverse aperture, A1, in the journal. Then the cap, E, is moved into place through the outer end of the hub and the screw, E6, placed into position. Then the nut, N, and the gasket, H4, are put into position in the chamber, E1. Then the locking plate, H, is forced into position against the cap, E, with its curved end edges in the channel, B5. Then the retaining plug, I, preferably a grease screw, is inserted through the locking plate aperture, H3, and into the nut, N. For removing the wheel from the journal, the several steps above stated are reversed.

To make springing of the locking plate easier and yet afford sufficient strength at the curved edges, the grooved edges may be made thicker and the body of the plate made thin-

ner, as shown in Fig. 12. In Fig. 13, the entire plate is made relatively thin and the curved edges folded over to give desired thickness and strength.

5 It is to be observed that my invention has no relation to the structure at the inner end of the hub, the end at the left in Fig. 1.

I claim as my invention:

1. In a structure of the kind described, the 10 combination with an axle journal, of a hub surrounding the journal and having an outer open end extending outward beyond the end of the journal, removable means near the end of the journal for engaging the journal 15 and the interior of the hub to hold the hub against outward movement on the journal, locking means located bodily within the interior of the outer part of the hub and removably inter-engaged with the interior of 20 the hub wall, and a cap extending into the hub between said locking means and the end of the journal.

2. In a structure of the kind described, the 25 combination with an axle journal, of a hub surrounding the journal and having an outer open end extending outward beyond the end of the journal and having the interior of the outer end channelled, removable means near the end of the journal for engaging the journal 30 and the interior of the hub to hold the hub against outward movement on the journal, a locking plate engaged in said channelling, and a cap extending into the hub between the locking plate and the end of the 35 journal.

3. In a structure of the kind described, the 40 combination with an axle journal, of a hub surrounding the journal and having an outer open end extending outward beyond the end of the journal and having the interior of the outer end channelled, removable means near the end of the journal for engaging the journal 45 and the interior of the hub to hold the hub against outward movement on the journal, a locking plate engaged in said channelling, a cap extending into the hub between the locking plate and the end of the journal, a nut resting in the cap, and a plug 50 extending through the locking plate and into the nut.

4. In a structure of the kind described, the 55 combination with an axle journal, of a hub surrounding the journal and having an outer open end extending outward beyond the end of the journal and having the interior of the outer end channelled, removable means near the end of the journal for engaging the journal 60 and the interior of the hub to hold the hub against outward movement on the journal, a locking plate engaged in said channelling, an apertured cap extending into the hub between the locking plate and the end of the journal, and a lubricant delivery plug 65 extending through the locking plate and into the aperture of the cap.

5. In a structure of the kind described, the 70 combination with an axle journal, of a hub surrounding the journal and having an outer open end extending outward beyond the end of the journal and having the interior of the outer end channelled, removable means near the end of the journal for engaging the journal 75 and the interior of the hub to hold the hub against outward movement on the journal, a locking plate engaged in said channelling, a cap extending into the hub between the locking plate and the end of the journal, a nut resting in the cap, and a plug extending through the locking plate and into the 80 nut and bearing against the outer face of the locking plate.

6. In a structure of the kind described, the 85 combination with an axle journal, of a hub surrounding the journal and having an outer open end extending outward beyond the end of the journal and having the interior of the outer end channelled, removable means near the end of the journal for engaging the journal 90 and the interior of the hub to hold the hub against outward movement on the journal, a locking plate engaged in said channelling, a cap extending into the hub between the locking plate and the end of the journal, a nut resting in the cap, and a lubricant receiving plug extending through the locking plate and threaded into the nut and bearing against the outer face of the locking plate.

7. In a structure of the kind described, the 100 combination with an axle journal, of a hub surrounding the journal and having an outer open end extending outward beyond the end of the journal and having the interior of the outer end channelled, removable means near the end of the journal for engaging the journal 105 and the interior of the hub to hold the hub against outward movement on the journal, a locking plate engaged in said channelling, and a cap extending into the hub between the locking plate and the end of the journal, said locking plate and said cap being apertured for the passing of lubricant into the hub.

8. In a structure of the kind described, the 110 combination with an axle journal, of a hub surrounding the journal and having an outer open end extending outward beyond the end of the journal and having the interior of the outer end channelled, removable means near the end of the journal for engaging the journal 115 and the interior of the hub to hold the hub against outward movement on the journal, a locking plate engaged in said channelling, and a cap extending into the hub between the locking plate and the end of the journal and having a flange extending around the journal and bearing against the inner horizontal face of the hub, said locking plate 120 and said cap being apertured for the passing of lubricant into the hub.

9. In a structure of the kind described, the combination with an axle journal, of a hub surrounding the journal and having an outer open end extending outward beyond the end of the journal and the interior of the hub having an annular shoulder directed toward the outer end of the hub and the interior of the outer end of the hub being channelled, a ring-form plate surrounding the journal and bearing against said shoulder, removable means on the journal for retaining said ring-form plate, a locking plate engaged in said channelling, and a cap within the hub and between said locking plate and the end of the journal.

10. In a structure of the kind described, the combination with an axle journal, of a hub surrounding the journal and having an outer open end extending outward beyond the end of the journal and the interior of the hub having an annular shoulder directed toward the outer end of the hub and the interior of the outer end of the hub being channelled, a ring-form plate surrounding the journal and bearing against said shoulder, removable means on the journal for retaining said ring-form plate, a washer between the ring-form plate and the retaining means, a locking plate engaged in said channelling, and a cap within the hub and between said locking plate and the end of the journal.

11. In a structure of the kind described, the combination with an axle journal, of a hub surrounding the journal and having an outer open end extending outward beyond the end of the journal and the interior of the hub having an annular shoulder directed toward the outer end of the hub, a ring-form plate surrounding the journal and bearing against said shoulder and being apertured for the passing of lubricant, removable means on the journal for retaining said ring-form plate, cap-retaining means located bodily within the interior of the outer part of the hub and removably inter-engaged with the interior of the hub wall, and a cap within the hub between said cap-retaining means and the end of the journal.

12. In a structure of the kind described, the combination with an axle journal, of a hub surrounding the journal and having an outer open end extending outward beyond the end of the journal and the interior of the hub having an annular shoulder directed toward the outer end of the hub, a ring-form plate surrounding the journal and bearing against said shoulder and being apertured for the passing of lubricant, removable means on the journal for retaining said ring-form plate, cap-retaining means located bodily within the interior of the outer part of the hub and removably inter-engaged with the interior of the hub wall, and a cap within the hub and between the cap-retaining means and

the end of the journal and having a flange extending along the inner horizontal face of the hub toward said ring-form plate.

13. In a structure of the kind described, the combination with an axle journal having near its end a transverse aperture, of a hub surrounding the journal and having an outer open end extending outward beyond the end of the journal and the interior of the hub having an annular shoulder directed toward the outer end of the hub and said hub having diametrically opposite apertures in a plane cutting said axle aperture, means including a cross pin extending through said journal aperture for holding the hub against outward movement on the journal, cap-retaining means located bodily within the interior of the outer part of the hub and removably inter-engaged with the interior of the hub wall, and a cap between said cap-retaining means and the end of the journal and extending over said hub apertures.

14. In a structure of the kind described, the combination with an axle journal, of a hub surrounding the journal and having an open outer end extending outward beyond the end of the journal, removable means near the end of the journal for engaging the journal and the interior of the hub to hold the hub against outward movement on the journal, locking means located bodily within the interior of the outer part of the hub and removably inter-engaged with the interior of the hub wall, and a metal cap extending into the hub between said locking means and the end of the journal and the face of said cap adjacent the end of the journal being chilled.

15. In a structure of the kind described, the combination with an axle journal, of a hub surrounding the journal and having an outer open end extending outward beyond the end of the journal, removable means near the end of the journal for engaging the journal and the interior of the hub to hold the hub against outward movement on the journal, locking means located bodily within the interior of the outer part of the hub and removably inter-engaged with the interior of the hub wall, a cap extending into the hub between said locking means and the end of the journal, and means extending laterally through the hub wall and engaging the cap to compel rotation of the cap in unison with the hub.

16. In a structure of the kind described, the combination with an axle journal, of a hub surrounding the journal and having an outer open end extending outward beyond the end of the journal, removable means near the end of the journal for engaging the journal and the interior of the hub to hold the hub against outward movement on the journal, a locking member removably engaged on the outer end of the hub, and a cap ex-

tending into the hub between said locking member and the end of the journal and having on its outer face a recess receiving said locking member.

17. In a structure of the kind described, the combination with an axle journal, of a hub surrounding the journal and having an outer open end, removable means near the end of the journal for engaging the journal and the interior of the hub to hold the hub against outward movement on the journal, a cap extending into the hub and across the end of the journal and bearing against the interior horizontal face of the hub, and cap retaining means located bodily within the interior of the outer part of the hub and removably inter-engaged with the interior of the hub wall.

18. In a structure of the kind described, the combination with an axle journal, of a hub surrounding the journal and having an outer open end, means for engaging the journal and the hub to hold the hub against outward movement on the journal, locking means located bodily within the interior of the outer part of the hub and removably inter-engaged with the interior of the hub wall, and a cap extending into the hub between said locking means and the end of the journal.

19. In a structure of the kind described, the combination with an axle journal, of a hub surrounding the journal and having an outer open end, means for engaging the journal and the hub to hold the hub against outward movement on the journal, locking means located bodily within the interior of the outer part of the hub and removably inter-engaged with the interior of the hub wall, and a cap extending into the hub between said locking means and the end of the journal.

20. In a structure of the kind described, the combination with an axle journal, of a hub surrounding the journal and having an outer open end, means for engaging the journal and the hub to hold the hub against outward movement on the journal, locking means located bodily within the interior of the outer part of the hub and removably inter-engaged with the interior of the hub wall, and a cap extending into the hub between said locking means and the end of the journal and having a flange extending inward along the inner face of the hub.

21. In a structure of the kind described, the combination with an axle journal, of a hub surrounding the journal and having an outer open end extending outward beyond the end of the journal and having the interior of the outer end channelled, removable means near the end of the journal for engaging the journal and the interior of the hub to hold the hub against outward movement on the journal, a flexible locking plate engaged in said channelling, and a cap extending into

the hub between the locking plate and the end of the journal.

In testimony whereof I have signed my name, this 9th day of January, in the year one thousand nine hundred and twenty-nine. ⁷⁰
WILLIAM O. McKAMEY.
